UNITED STATES PATENT OFFICE.

JOTHAM R. HILLMAN, OF SHORTSVILLE, NEW YORK.

DESIGN FOR A KNIFE FOR SLICING-MACHINES.

SPECIFICATION forming part of Design No. 31,752, dated October 31, 1899.

Application filed October 4, 1899. Serial No. 732,572. Term of patent 14 years.

To all whom it may concern:

Be it known that I, JOTHAM R. HILLMAN, of Shortsville, county of Ontario, and State of New York, have invented a new and useful 5 Design for a Knife for Slicing-Machines, of which the following is a specification.

This invention has reference to a design for a knife for use in slicing-machines; and the invention consists in the peculiar configuration represented in the accompanying drawings, in which—

Figure 1 is a plan view of the knife. Fig. 2 is a view showing its sectional form.

The essential or leading features of my design are the flat rectangular body portion *a* and the inclined lip *b*, forming a continuation of the body portion. The edge *c* of the lip extends parallel to the edges of the body portion and joins the same by divergent lines *d*.

In cross-sectional view, as in Fig. 2, the 20 plane of the lip *b* is inclined with reference to that of the flat body and joins the same by an inclined portion *e*, disposed in a plane inclined with respect to those of the body portion and lip. 25

Having thus described my invention, what I claim is—

The design for a knife as herein shown and described.

In testimony whereof I hereunto set my 30 hand, this 22d day of September, 1899, in the presence of two attesting witnesses.

JOTHAM R. HILLMAN.

Witnesses:

IRA DIBBLE,
MARTIN B. DAWSON.
